UNITED STATES PATENT OFFICE.

CHARLES H. COTHRAN, OF FORT COBB, OKLAHOMA.

PORTABLE VISE.

Application filed May 16, 1927. Serial No. 191,855.

This invention relates to a portable vise and has as its general object to provide a novel vise structure in combination with a wheeled body adapting the vise to be employed in fields 5 and readily moved about from place to place.

With this and other objects in view, my invention will be better understood from a description of the same when taken in connection with the accompanying drawings, where- 10 in:

Figure 1 is a top plan view of the device;

Figure 2 is a front elevation;

Figure 3 is a vertical sectional view on the line 3—3 of Figure 1;

Figure 4 is a detail horizontal sectional view through the vise structure;

In the drawings the numeral 1 designates the body of a cart.

The vise embodying the invention consists 20 of a support bar 14 of a configuration to provide a horizontal flange 15 and a vertical flange 16. The horizontal flange 15 is directly secured to the top 17 of cart body 1 by the bolts 18 which are encircled by the sleeves 19 25 that are interposed between the flange 15 and the said top, and thus the bar is effectively secured to and spaced a predetermined distance above the body. The vertical flange 16 is provided with openings 20 to have inter- 30 locking engagement with the L-shaped extremities 21 of the companion vise jaws 22. These jaws 22 have threaded engagement with feed screws 23 that have head portions 24 rotatably mounted in the vertical flange 16 and 35 held in place by the clip 25. A handle 26 is secured to the feed screw to facilitate turning of the latter.

The body is supported upon a frame 27 directly secured to the receptacle and in turn 40 supported by the wheels 28. A tongue 29 extends from the frame and carries the handle 30, by means of which the apparatus may be readily moved.

I claim:

45 1. A vise comprising a stationary jaw mem-

ber having an opening therein and a perpendicular slot spaced from the opening, a jaw member comprising a body portion opposing the first mentioned member, a shank at one end of the body portion fitting through said slot and provided at its end with a head engaging behind first mentioned jaw member, the second mentioned jaw member having a threaded opening therein adjacent its other end, and an adjusting screw having a headed 50 end swiveled in said opening and a threaded stem fitting through the threaded opening in the second mentioned jaw member, and a handle at the other end of the said stem providing means whereby the stem may be rotatably ad- 55 justed to effect adjustment of the second men- tioned jaw member with respect to the first mentioned jaw member.

2. A vise comprising a stationary jaw mem- 60 ber having a perpendicular slot therein and an opening spaced with respect to the slot, an adjustable jaw member comprising a body portion opposing the first mentioned jaw member, a shank at one end of the body portion engaging through said slot, a head at the 65 end of the shank engageable with the face of the first mentioned jaw member opposite the face which opposes the adjustable jaw mem- 70 ber, a retaining member secured to the said face of the first mentioned jaw member and including a portion extending opposite and in spaced relation to the opening in said mem- 75 ber, the adjustable jaw member having a threaded opening therein, an adjusting screw having a headed end rotatably fitted in the 80 opening in the first mentioned jaw member and engaged by the said portion of the retaining member, the said adjusting screw being threaded through the said opening in the ad- 85 justable jaw member, and a crank handle upon the other end of said adjusting screw.

In testimony whereof I affix my signature.

CHARLES H. COTHRAN.
